STOCKING

Henry R. Hinkley, Lebanon, Pa., assignor to
NoMend Hosiery, Inc., Philadelphia, Pa., a corporation of Pennsylvania

Application March 20, 1947, Serial No. 735,973

3 Claims. (Cl. 66—187)

1

This invention relates to seamed full fashioned stockings, particularly to that variety which is produced from blanks which are flat knitted complete with leg and foot in a single operation on straight knitting machines of the "Cotton" type. It has been quite common heretofore to form laterally-projecting heel cheeks on continuous integrally knit flat stocking blanks by transferring groups of end loops outwardly in successive courses of the knitting at a constant rate, and by correspondingly increasing the travel of the yarn carriers of the producing machines. However, due to the imposed necessity for terminating the heel widenings at prescribed points on the blanks, the possibility of securing properly proportioned heel cheeks by the customary method was very limited. In other words, the formation of heel cheeks of acceptable length (height) necessitated outward transfer of relatively small groups of end loops with consequent compromise in the heel widths; whereas the formation of heel cheeks of acceptable widths entailed the transfer of larger groups of end loops to the disadvantage of unduly lengthening the cheeks.

My invention is directed toward overcoming the above drawbacks, that is to say: it has for its aims to provide stockings of the kind referred to with heels which are not only properly dimensioned as to length and width, but properly shaped and proportioned for different nominal foot sizes; and moreover, to provide a simple method whereby blanks for stockings having these attributes can be expeditiously and inexpensively produced in quantity.

How the foregoing objectives are realized in practice is set forth in the detailed description hereinafter of the attached drawings, wherein Fig. 1 shows, in side elevation, a lady's stocking conveniently embodying my invention.

Fig. 2 is a fragmentary view of the unseamed flat selvaged blank for the stocking as it appears upon removal from the producing machine.

Fig. 3 is a fragmentary view of the area of the blank indicated by the rectangle III in Fig. 2, showing the interloopment in one of the heel cheeks and, more or less diagrammatically, the parts of the knitting machine utilized in the formation of such cheek in accordance with my invention.

Figs. 4 and 5 are fragmentary views corresponding to Fig. 2 and showing modifications of my invention.

My improved stocking as shown in Fig. 1 is 55 11 so that the corresponding outer edge portions

5 integrally knit throughout complete with leg 5 and foot 6, in one continuous operation on a flat knitting machine having, as conventionally represented in Fig. 3, a straight series of needles 7 and a longitudinally reciprocating yarn carrier 8. For use in forming the heel 9, the machine is further provided with two combs such as the one indicated at 11, having transfer points 12, and with two covering plates such as the one indicated at 13. Except for its heel, the stocking is of conventional construction. After common practice the leg 5 of the stocking is shaped by narrowing with incidental formation at each side of a narrowing line 15 and 16 immediately below the top welt 17 and in the region of the calf 18. The foot 6 may be finished with a conventional diamond point toe 19 as illustrated by way of example, or in any other approved or desired manner.

10 20 25 30 35 40 45

The heel, with which the present invention is more especially concerned, results from the formation at each side edge of the blank, a laterally extending cheek or tab 20 which terminates in a square bottom 21 and meets with corresponding side edge 22 of the instep in a square corner at 23. Each heel tab is connected to the body of the blank by a suture line composed of two connecting segments 25, 26 which lie at an obtuse angle to each other and are both inclined with respect to the longitudinal median of the blank, the segment 25 being, in this instance, considerably longer than the segment 26 and the latter extending to the corner juncture 23 between the cheek bottom 21 and the instep edge 22. The side edge portion 21 of each heel bottom is parallel with the longitudinal median of the blank and has a marginal portion 28 set apart by a fashioning suture 29, in which the wales run straight, while those in the rest of the tab are inclined and parallel with the suture segment 25, and the side edge of 30 of the upper portion of the cheek.

The blank 10 for the stocking is knitted in the usual manner down through the leg 5 to the completion of the ankle at the line 31—31 in Fig. 2. At this stage, the transfer point combs 11 are placed in operation, and as the knitting proceeds, the loops from definite numbers of end needles are transferred outwardly in alternate courses each time to the next adjacent needles with incidental formation of the suture segments 25. During this phase, the traverse of the yarn carrier 8 is increased concurrently with the alternate outward shifts of the transfer point combs

30 of the blank are sloped in parallel relation to the suture segments 25. Upon attainment of the desired maximum width during the last described phase of the knitting—in this instance at the line 32a—32a, the traverse of the carrier 8 is kept constant and the cover plates 13 are placed in operation to prevent transfer of loops beyond the needles at 1a during the next phase of the knitting. As a result, the straight wale margins or marginal portions 28 are begun with incidental initiation of fashioning sutures 29 inward of the opposite side edges of the blank. The last described procedure is followed until a line 32—32 is reached at which the upper portions of the heel cheeks are completed. In the knitting which immediately follows, the point combs are given idle outward shifts between active dips in alternate courses without change in the constant traverse of the carrier 8. Loops are thereby transferred each time from wales within the body of the blank spaced by two instead of by one in alternate courses, with attendant formation of suture segments 26 in direct continuation of the segments 25, at an obtuse angle to them, and with prolongation of the straight wale margins 28 and their defining sutures 29 to the completion of the lower portions of the heel cheeks at the line 21—21. At the line 21—21 the traverse of the yarn carrier 8 is reduced to the desired width of the instep between the points 23—23. After the knitting of a few courses to a line 33—33 to form the short fabric section with parallel side edges immediately beyond the heel cheeks, the traverse of the carrier is progressively reduced for a time to form a narrowed section with inwardly sloped side edges as at 34 until a line 35—35 is reached, whereafter the traverse of the carrier 8 is maintained constant during knitting of the foot to the course at which the toe 19 is to be begun in the customary manner.

The width of the heel cheek bottoms and the shape of the outer corners of said cheeks may be varied in accordance with my invention, by beginning the use of the cover plates 11 earlier than above exemplified during the knitting of the upper portion of the heel cheeks; by delaying the use of said combs until the line 32—32 is reached; or by still further delaying their use until some time after the line 32—32 is reached. The results of the two latter alternatives are shown in Figs. 4 and 5 respectively. In Fig. 4 the use of cover plates was begun at the line 32—32 concurrently with starting of the second phase of the heel cheek knitting; while in Fig. 5, the use of said plates was begun later at a line 32b—32b beyond the line 32—32 and during the second phase of heel cheek knitting.

I do not, of course, consider myself limited to the precise procedures above set forth by way of example, since considerable further variations are possible within the scope of the appended claims without departing from the spirit of the invention. Thus, for example, the proportioning of the heel cheeks may be changed by increase

or decrease in the number of heel needles employed with corresponding changes in the traverse of the yarn carrier; and by affecting the transfers in more remotely spaced courses; and/or increasing the idle shifts of the narrowing combs between dips.

Having thus described my invention, I claim:

1. A stocking formed from an integrally knit fashioned flat blank complete with leg and foot, characterized by having at its opposite side edges, angularly offset laterally extending heel cheeks beginning at the completion of the ankle and terminating in transverse edge segments beyond the side edges of the instep, the upper portions of the heel cheeks being outwardly displaced by progressive transfer of loops from spaced wales within the body of the blank to the extent of at least one wale in spaced courses, and whereof the lower portions are displaced outwardly by progressive transfer of loops from wales within the body of the blank spaced by a greater distance than in the upper portion, the sutures resulting from the transferring having segments at an obtuse angle to each other both inclined to the longitudinal axis of the blank and terminating at the juncture corners between the heel cheek bottoms and the side edges of the instep.

2. A stocking according to claim 1, further characterized in that the widening at the outer bottom corners of the heel cheeks is terminated at definite wales inward from the side edges of the blank with the resulting sutures extending along said definite wales parallel to the longitudinal axis of the blank.

3. A stocking according to claim 1, whereof the blank is further characterized by having, immediately beyond the heel cheeks, a short section of uniform width with parallel side edges extending from the inner terminals of the traverse edge segments; and a narrowed portion between said short section and the foot portion of the blank.

HENRY R. HINKLEY.
